CLAIM

The ornamental design for a scoreboard, as shown and described.

DESCRIPTION

FIG. 1 is a front, top, right isometric view of a scoreboard; FIG. 2 is a rear, bottom, left isometric view of the scoreboard of FIG. 1;

FIG. 3 is a front elevational view of the scoreboard of FIGS. 1-2;

FIG. 4 is a rear elevational view of the scoreboard of FIGS. 1-3;

FIG. 5 is a side elevational view of the scoreboard of FIGS. 1-4;

FIG. 6 is another side elevational view of the scoreboard of FIGS. 1-5;

FIG. 7 is a top plan view of the scoreboard of FIGS. 1-6; and,

FIG. 8 is a bottom plan view of the scoreboard of FIGS. 1-7. The thin dash-dash-dash lines are for the purpose of illustrating environmental structure and form no part of the claimed design.
